UNITED STATES PATENT OFFICE.

SIEGMUND BACHMANN, OF CHICAGO, ILLINOIS.

COAT-HANGER.

1,251,461.

Specification of Letters Patent.

Patented Jan. 1, 1918.

Application filed February 6, 1917. Serial No. 146,933.

To all whom it may concern:

Be it known that I, SIEGMUND BACHMANN, a citizen of the United States, residing at Chicago, in the county of Cook and State of Illinois, have invented a new and useful Improvement in Coat-Hangers, of which the following is a specification.

My invention relates more particularly to coat-hangers constructed of cardboard or similar material provided more especially for use in combination with containers, such as boxes, for receiving garments, including coats, wherein the garment-hanger extends through a slot in a side of the container and by which the container is suspended either on a hook, in the case of storage, or from the hand of a person grasping the protruding part of the hanger.

My object is to provide a hanger which may be economically constructed and which shall present the requisite degree of strength for supporting a coat, especially when the latter is folded over the hanger and inclosed in a container of the character above referred to, wherein the garment is maintained in unmussed condition.

Referring to the accompanying drawings,—

Figure 1 is a perspective view of a suit container and hanger, the latter being constructed in accordance with my invention.

Figs. 2 and 3 are similar views of the two telescoping- sections forming the box of Fig. 1.

Fig. 4 is a perspective view of the hanger.

Fig. 5 is a broken view in section taken through the top of the box, through which the handle portion of the hanger extends; and Fig. 6, a section taken at the line 6 on Fig. 5 and viewed in the direction of the arrow.

In the accompanying drawing I have illustrated my improved hanger as provided more especially for coöperation with a suit-container wherein the upper portion of the hanger extends through a side of the

container and serves as a means of supporting the latter. Such a box is represented at 7, it being formed of the two telescoping sections 8 and 9 containing registering slots in one side, as indicated at 10 and 11.

The hanger represented at 12 is formed of relatively heavy board, such as pasteboard, presenting at its upper edge a handle-section 13 containing a slot 14, which is adapted to be projected through the slot in the box, as represented in Fig. 1. The body of the hanger is reinforced by the sections 16 and 17, each of which at its upper end is of the shape of the section 13 of the body-portion and is provided with a wing 19. The members 16 and 17 lie flatwise together and the member 17 flatwise against the body-portion, these reinforcing sections being so disposed that the wings 19 extend beyond the sections carrying them and overlap the portion of the body of the hanger below the section 13, and in this position are secured to the body as by the staples 18, the upper edges of the wings 19 being preferably substantially flush with the upper edges 15 of the body. In the actual manufacture of the hangers these reinforcing members 16 and 17 may be cut from what would otherwise be the waste board at the upper corners of the hangers.

What I claim as new and desire to secure by Letters Patent is:

A garment-hanger comprising a body section of sheet material, and having a relatively narrow section at its upper end, and reinforcing members carried by the hanger and arranged flatwise relative to said section and the adjacent part of said body portion, said reinforcing members being each provided with a part which projects from one end only thereof, with said members so arranged that said projecting portions extend in opposite directions from and beyond said section.

SIEGMUND BACHMANN.
